CLAIM

The ornamental design for a triangular-shaped fishing reel holder, as shown and described.

DESCRIPTION

FIG. 1 is a front elevation view of a fishing reel holder showing my design;

FIG. 2 is a side elevation view of the fishing reel holder shown in FIG. 1; and,

FIG. 3 is a bottom view of the fishing reel holder shown in FIG. 1.

FIG. 1.

FIG. 3.

FIG. 2.
